US00D792164S

(12) **United States Design Patent** (10) **Patent No.:** **US D792,164 S**
(45) **Date of Patent:** **** Jul. 18, 2017**

(54) **FOOD DISPENSER**

(71) Applicant: **Gehl Foods, Inc.**, Germantown, WI (US)

(72) Inventors: **Thomas Mitchell**, Chicago, IL (US); **Anders Olof Rostlund**, Chicago, IL (US); **David Mucci**, Chicago, IL (US)

(73) Assignee: **Gehl Foods, LLC**, Germantown, WI (US)

(**) Term: **14 Years**

(21) Appl. No.: **29/501,025**

(22) Filed: **Aug. 29, 2014**

(51) LOC (10) Cl. **07-06**

(52) U.S. Cl.

USPC **D7/589**

(58) **Field of Classification Search**

USPC D7/594, 590, 591, 592, 593, 595, 596, D7/597, 598, 599, 600, 300, 300.1, 300.2, D7/301, 302, 303, 304, 305, 312, 316, D7/317, 318, 319, 321, 322, 589, 601, D7/602, 613, 702, 703, 628, 629, 637, D7/638, 639, 368, 669, 309, 310, 311, D7/314, 320, 608; D9/600, 716, 719, D9/503, 505, 504, 439, 443, 447, 440, D9/454, 446, 436, 448, 449, 450, 451, D9/452, 453, 455; D20/1

(57) **CLAIM**

We claim the ornamental design for a food dispenser, as shown and described.

DESCRIPTION

FIG. 1 is a top, front, right perspective view of the claimed design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines shown in FIGS. 1-7 represent portions of the food dispenser that form no part of the claimed design.

1 Claim, 5 Drawing Sheets
